UNITED STATES PATENT OFFICE.

HERMANN STEINHART, OF STUTTGART, GERMANY, ASSIGNOR TO THE FIRM OF
ROBERT BOSCH, OF STUTTGART, GERMANY.

BRUSH-HOLDER FOR DYNAMOS.

1,073,643.

Specification of Letters Patent. Patented Sept. 23, 1913.

Application filed August 13, 1912. Serial No. 714,770.

To all whom it may concern:

Be it known that I, HERMANN STEINHART, a subject of the German Emperor, residing at Lerchenstrasse 74th, Stuttgart, Germany, 5 have invented certain new and useful Improvements in Brush-Holders for Dynamos; and I do hereby declare the following to be a full, clear, and exact description of the invention, such as will enable others skilled in 10 the art to which it appertains to make and use the same.

The present invention relates to a construction of brush holders for dynamos, and particularly to one well adapted for small 15 machines such as ignition current generators for internal combustion engines, whereby the conductor to the generator may be conveniently and reliably connected electrically and mechanically to the collector 20 brush.

In the accompanying drawings, Figure 1 represents a longitudinal section of the preferred form of my invention; Fig. 2 represents a view looking from the right of Fig. 25 1; and Fig. 3 represents a modified form of clamping means.

The member *a*, preferably of insulating material, has a longitudinal bore *g* passing through the member and screw-threaded 30 near one or both ends, as at *c*, and a second bore *h* at an angle to the longitudinal bore and extending outwardly therefrom. This second bore is provided with a sleeve *b* of metal in which the spring-pressed collector 35 brush *j* slides in order to maintain contact with a collector or commutator on the generator (not shown). The brush holder is fastened to the generator at the eye *m*.

The hollow cylinder *d* of metal is fitted 40 securely in the longitudinal bore *g* so as to be in contact with the metal sleeve *b* and in electrical connection with the collector brush *j*. This cylinder has a special shaped interior, preferably a cylindrical central portion and flared ends. The hollow cylinder *d* may be securely fitted in the longitudinal bore in any suitable manner, but preferably in cases where the member *a* is of insulating material, by making the outer diameter 45 of the sleeve *d* slightly larger than the diameter of the bore *g*, and then inserting the sleeve *d* into place before the member *a* is hardened by vulcanizing.

The clamping screw *f* preferably has a

conical end *k* and an annular bearing *l* at 55 the base of the cone, so that when it is screwed into the longitudinal bore of the member *a*, the uninsulated strands are forced apart from the center of the conductor *e* and are jammed fast against the 60 flaring end of the cylinder *d* by the conical end of the screw, and also against the flat end of the cylinder *d* by the annular bearing *l*. By this construction the conductor *e* may be inserted in either end of the longitudinal bore *g* while the screw *f* enters the 65 other end thereof, preventing the conductor from being pulled out and also securely holding it in good electrical connection with the collector brush *j*. 70

In the modification shown in Fig. 3, the flat bearing at the base of the conical end *k* is omitted, the uninsulated end of the strands being held fast against the flaring part of the internal bore of the cylinder *d* 75 without being forced against the ends thereof.

Having thus described my invention, what I claim is:

1. In a brush holder and conductor clamp 80 for dynamos, a member having a longitudinal bore passing therethrough and a second bore at an angle to the longitudinal bore, a metal sleeve mounted in said second bore to receive and make electrical connection with 85 a collector brush, a hollow cylinder of metal mounted in the longitudinal bore and electrically connected with said sleeve, and means at one end of said sleeve for holding the uninsulated end of an electrical conductor, which enters the other end of the longitudinal bore, in contact with said cylinder to electrically connect the conductor 90 with the collector brush.

2. In a brush holder and conductor clamp 95 for dynamos, a member having a longitudinal bore passing therethrough, and a second bore at an angle to the longitudinal bore, a metal sleeve mounted in said second bore to receive and make electrical connection with 100 a collector brush, a hollow cylinder of metal having a flaring terminal bore and mounted in the said longitudinal bore, and a screw at one end of the longitudinal bore having a tapered end adapted to enter the flaring bore of said cylinder to hold the uninsulated end of a stranded electrical conductor, which enters the other end of the longitudinal 105 bore.

nal bore, in contact with said cylinder to electrically connect the conductor with the collector brush.

3. In a brush holder and conductor clamp for dynamos, a member having a longitudinal bore passing therethrough, and a second bore at an angle to the longitudinal bore, a metal sleeve mounted in said second bore to receive and make electrical connection with 10 a collector brush, a hollow cylinder of metal having a flaring terminal bore and mounted in the longitudinal bore, and a screw at one end of the said longitudinal bore having a tapered end adapted to enter the flaring 15 bore of said cylinder and also having a flat bearing at the base of the tapered end to hold the uninsulated end of a stranded conductor, which enters the other end of the longitudinal bore, in contact with said cylinder to electrically connect the conductor 20 with the collector brush.

4. In a brush holder and conductor clamp for dynamos, a member having a longitudinal bore passing therethrough and screw-threaded near both ends, a hollow cylinder of metal mounted in the longitudinal bore, and a screw engaging the threads of the lon-

30

itudinal bore at one end or the other and adapted to hold the uninsulated end of an electric conductor, which enters the opposite end of the longitudinal bore, in contact with said cylinder.

5. In a brush holder and conductor clamp for dynamos, an insulator having a longitudinal bore passing therethrough and screw-threaded at both ends, a hollow cylinder of metal mounted in the longitudinal bore, and having flared openings at the ends, and a screw with a tapered end and an annular bearing at the base of the tapered end, 30 said screw engaging the screw-threads at one end or the other of the longitudinal bore and adapted to hold the uninsulated end of a stranded electric conductor which enters the opposite end of the longitudinal bore, 35 in contact with the flared interior and the end of said cylinder.

In testimony whereof I affix my signature, in presence of two witnesses.

HERMANN STEINHART.
